UNITED STATES PATENT OFFICE.

OSCAR A. BERMAN, OF CINCINNATI, OHIO.

OVERALLS AND SUSPENDERS.

1,256,768.

Specification of Letters Patent. Patented Feb. 19, 1918.

Application filed October 1, 1917. Serial No. 194,196.

To all whom it may concern:

Be it known that I, OSCAR A. BERMAN, a citizen of the United States, and a resident of Cincinnati, State of Ohio, United States 5 of America, have invented certain new and useful Improvements in Overalls and Suspenders, of which the following is a specification.

This invention relates to improvements in 10 suspenders and especially to improvements in suspenders for overalls.

An object of the invention is to provide in combination with shoulder straps and rear straps of suspenders a readily removable 15 elastic connecting web, which if attached to the shoulder and rear strap will impart to the entire suspenders the necessary elasticity.

It is another object of the invention to 20 provide an elastic connecting web which may be readily removed so as to permit of the laundering of the overalls, shoulder and rear straps, without compelling the user also to laundry the elastic.

25 Another object of the invention is to provide in an overall or suspenders a connecting web which has several plies or layers separated from each other, this web being constructed in the form of an endless belt supported at opposite points on freely rotatable sleeves loosely mounted on shanks of supporting buckles.

Another object of the invention is to provide in connection with a suspender, and 35 especially with an overall suspender, a number of buckles, preferably all of the same construction, which form supports for the folding or turning points of the shoulder straps and rear straps and for the turning 40 points of the connecting web, all of these buckles being interlinked with each other and being readily closable or adapted to be opened, so that the removal or insertion of the connecting web can easily be effected.

45 It is finally an object to provide an elastic web which owing to its movability with respect to its supporting points is inclined to bring at different times different portions in contact with the back of the wearer so as to 50 retard for a long time that injury which is caused to fabrics by contact with materials impregnated with perspiration.

An embodiment of the invention is illustrated in the accompanying drawing in

which similar reference characters refer to 55 similar parts. In the drawing—

Figure 1 shows a rear view of the suspender in use.

Fig. 2 shows on a larger scale the connecting element between shoulder straps and 60 rear straps combined with the interlinking buckles, and

Fig. 3 shows in perspective view one of these buckles for the connecting web.

The overalls 1 are provided with straps 65 2 which may be buttoned or sewed to the waistband at the rear of the same, while the shoulder straps 3 may be fastened in a similar way to the front portion of the garment. The connection between the shoulder straps 3 and the rear straps 2 of the suspenders is effected by a third strap 5. This connecting element 5 may be made of resilient or elastic fabric and is connected with the shoulder and rear straps of the suspender 70 75 in such manner that it can readily be removed and attached, whenever desired.

For this purpose this connecting element is constructed as an endless belt. The turning points of this endless belt or connecting 80 web 5 are formed by sleeves or rollers 6 loosely mounted on the shanks 7 of buckles 8. These buckles are constructed similar to ordinary safety pins, having at the end opposite the bight a closing loop 9 into which 85 the free end of the pin 10 may be inserted. This pin has a looped lateral extension 11 with which a similar looped extension of the next buckle is interlinked. Another portion of the elastic connecting web is also 90 trained about a sleeve 6 of an identical buckle 8 and the front and rear straps, which may be fastened to the waistband of the overalls, are turned or folded about a sleeve 95 6 forming part of that buckle which is interlinked with the other buckles just mentioned.

It is obvious therefore that a removal of the elastic web from the suspenders may readily be effected, for instance, by simply 100 detaching the two outermost buckles from their connection with the shoulder straps and rear straps respectively, so that the non-elastic elements of the overall and suspenders may be washed. It is also obvious that, 105 owing to the loose interlinking connection of the several buckles, no motion of the body of the wearer will encounter any resistance

in the material of the suspender, but that owing to the provision of these buckles and of the elastic endless web, the suspender will follow the motion of the body of the 5 wearer, no matter in which direction and how far it is moved.

This construction also has the advantage that with the exception of joining the loose ends of the connecting strap 5, so as to 10 form an endless web, no sewing is necessary, while if a single strap is used, as, for instance, described in the specification pertaining to my co-pending application, Serial Number 162,975, the ends of the detachable 15 interconnecting strap must be reinforced with tape or some other strong fabric.

Owing to the fact that the endless web has a tendency to revolve about the shanks and about the sleeves loosely secured to these 20 shanks, the endless web will have a tendency to bring at different times different portions in contact with the sleeve and therefore also in contact with the back of the wearer, this 25 change of the position of the portions of the elastic strap taking place whenever the garment is removed or whenever the elastic web is removed, or to a certain extent even with each motion of the body of the wearer. The result will be that that side of the elastic 30 strap which was close to the body of the wearer, and which has been dampened by perspiration, may at intervals be exposed to the air and become dry before the acids of the perspiration have had time to permanently 35 injure certain parts of the web.

I claim:

1. In a suspender in combination with shoulder straps and rear straps, an endless elastic web inserted between said straps, a 40 buckle held to the shoulder strap, another

buckle interlinked therewith and supporting the connecting web, a buckle connected with the rear strap, and another buckle interlinked with said last mentioned buckle and also in engagement with the endless connecting web. 45

2. In a suspender in combination with shoulder straps and rear straps, an endless connecting web, a buckle in the form of a safety pin having a shank passing through 50 the space between adjacent portions of the shoulder strap, a sleeve loosely mounted on said shank, another buckle interlinked with said first named buckle and having also a shank, a loose sleeve on said shank passing 55 through the interspace between two portions of the connecting web, and another pair of buckles in similar arrangement with respect to each other, to the connecting web and rear strap. 60

3. A suspender comprising in combination with shoulder straps and rear straps, an endless connecting web, a buckle having a shank, a sleeve on said shank passing through adjacent portions of the shoulder straps, a pin 65 forming part of the buckle and provided with an extension, another identical buckle having an extension on its pin interlinked with the extension on the pin of the first named buckle, the shank of the second 70 named buckle being provided with a loosely mounted sleeve over which the connecting web is trained, another pair of interlinked buckles, the shank of a buckle of the last 75 named pair being movably attached to the rear strap, and the shank of the other buckle of the last named pair having a sleeve over which the connecting web is trained.

OSCAR A. BERMAN.
